UNITED STATES PATENT OFFICE.

EDWARD A. TABER AND ANDREW G. SPINNEY, OF PORTLAND, MAINE.

PILOT-LIGHT CONTROL.

Application filed July 1, 1925. Serial No. 40,781.

This invention relates to pilot light controlling devices having for its object the control of a pilot light, the same being intended more particularly though not exclusively for 5 use with liquid fuel burners, such that the pilot light may be reduced in volume during the time when its full flame is not required.

The invention will be best understood by reference to the following description when 10 taken in connection with the accompanying illustration of one specific embodiment thereof, while its scope will be more particularly pointed out in the appended claims.

In the drawings,—

Fig. 1 is an elevation of a conventional form of liquid fuel burner with the pilot light controlling device applied thereto;

Fig. 2 is an elevation in section, taken in part through the controlling valve and in 20 part through the attached transformer; and

Fig. 3 is a sectional detail in plan showing the shape of the valve stem and the surrounding passage.

Referring to the drawings, and particularly to Fig. 1, we have there shown such parts of a conventional form of oil burner as are necessary to an understanding of the present invention.

The burner comprises the rotary nozzle 11, located within the firepot 13 of the heater 15, the nozzle being rotated by a motor 17 arranged in the space beneath the firepot and mounted to rotate about a vertical axis. The nozzle is connected through a hollow shaft 19 with a motor-driven gear pump 21, through which commingled air and liquid fuel are supplied under pressure to the nozzle and distributed and burned in the combustion chamber of the firepot.

The feed motor 17, which supplies the liquid fuel under pressure in the form of commingled air and oil, is supplied with current through the cable connection 23 and a conventional type of controlling switch, the latter arranged within the casing 25 and connected with the main line circuit 27, the switch being capable of being thrown to close the motor circuit by means of the room thermostat 29 controlling the switch through the circuit 31. As is usual in this class of devices, when the temperature falls and the thermostat 29 acts, the switch 25 closes the motor circuit, the latter starts into operation feeding air and oil to the burner, and the burner continues in operation until a rise in the room temperature causes the thermo-

stat to close the thermostat circuit 31 and, acting through the switch 25, to open the motor circuit and cut off current from the main power line 27.

The liquid fuel burner is also provided with the usual pilot light 33, the burner of which is supplied with gaseous fuel through the supply pipe 35. During the time that the main burner is out of action and the motor at rest, it is unnecessary that the pilot light burn under its full volume. Accordingly, we have herein provided a simple but effective form of controlling device in the form of an electrically actuated valve adapted to supply the pilot light burner with a reduced volume of gas during such period as the burner is out of action, but to increase that volume to its full amount when the burner is started in operation, and preferably to maintain it at its full volume during the entire period of main burner operation.

In Fig. 1 this valve is shown connected in the pilot light supply pipe 35 and is shown in detail in Fig. 2. Referring more particularly to Fig. 2, the controlling valve comprises a casing 37 having the inlet 39 connected to the source of gas supply and the outlet 41 connected to the gas supply pipe 35 leading to the pilot light burner. The 85 inlet 39 communicates through the passage 43 with the overhead chamber 45 which is enclosed by the cap piece 47, the chamber 45 opening to the outlet 41 through the longitudinal supply port 49. During such time 90 as the main burner is out of operation, the port 49 is closed by the conical valve 51 which seats against the upper edges of the port, means being provided, as will hereafter appear, to raise the valve to open the 95 port and admit the full volume of gas supply to the pilot light when the main burner is started into operation.

While the main burner is out of operation a small volume of gas is admitted to 100 the outlet 41 through a by-pass 53, which latter comprises a right-angled passage communicating with the bottom of the chamber 45 and opening laterally into the port 49. The amount of gas passing 105 through the by-pass may be regulated by the adjusting screw 55 by means of which the amount of gas passing through the by-pass passage may be restricted more or less at will. While the main burner is out of 110 operation, therefore, a restricted quantity of gas passes around the valve 51 through

the by-pass 53 into the outlet 41 and to the pilot light burner, maintaining the latter at a reduced volume.

In order to open the valve and supply the full volume of gas to the pilot light burner when the main burner starts into operation, the valve 51 is surmounted by and attached to the disk armature 57 preferably of soft iron, which armature is co-operatively related to the poles of a pair of magnets 59 (one only of which appears in Fig. 2). The latter are adapted to be energized when the main burner is started up to raise the armature and lift the valve and open the port 49 to the space 45. When the magnets 59 are deenergized, the valve again drops to its closed position.

To guide the valve in its movements between its opened and closed positions, it is preferably provided with a stem 61 which has guiding contact with the walls of the port 49 but is so shaped as to leave ample passage for the gas through that part of the port below the valve. Herein, as will appear from Fig. 3, the stem 61 is cut away on three sides to give a generally triangular cross section, the stem having free sliding contact with the walls of the port adjacent the apexes of the triangle.

Various means may be utilized for energizing the magnets 59 and opening the gas valve when the main burner starts into operation through the action of the thermostat 29. Herein we have utilized the motor current for that purpose, the magnets 59 being connected through the binding posts 65 and 67 and the leads 69 with the secondary 71 of a small transformer 73 which is attached to the casing 37. The primary 75 of the transformer is connected through the leads 77 in shunt to the motor circuit, so that when the thermostat acts to connect the motor to the main line through the switch 25, the magnets 59 are energized, the armature lifted and the valve 51 opened. When the motor circuit is again opened through the action of the thermostat 29, the magnets 59 are deenergized, the armature drops and the valve moves to its closed position, cutting off the main gas supply and permitting only the reduced volume of gas to flow through the by-pass to the pilot light burner.

While we have herein shown and de-

scribed for purposes of illustration one specific form of pilot light control device, it is to be understood that various modifications thereof may be employed and other applications thereof made and other means for controlling the same may be utilized, all within the spirit of the invention.

Claims:

1. A pilot light control valve for a liquid fuel burner or the like comprising a casing, a hollow cap therefor, the cap co-operatively related to the casing to form a chamber, a valve controlled port with a by-pass for the port, a valve normally arranged to close the port and having a stem provided with a part of magnetic material in co-operative relation with the magnet winding, an electrically controlled device for energizing the magnet to open the valve and increase the volume of fuel supply to the pilot light burner during the time the burner is in operation.

2. A pilot light control valve for a liquid fuel burner or the like comprising a casing and a cap therefor, the cap co-operatively related to a depression in the casing to form a supply chamber, said chamber having an inlet passage and a longitudinally arranged exit passage, the latter being of circular cross section and having a valve controlled port in said casing at the bottom of the chamber and connected to a suitable outlet passage, said casing having also a by-pass leading from said chamber to the exit passage beyond said port, means to regulate the flow of gas through said by-pass, a valve adapted to seat against and close the port, the valve having a guiding stem of non-circular cross section extending into the exit passage permitting the bypassed fuel to flow in said exit passage and having also a part of magnetic material located above the port, a magnet winding within the cap and adapted when energized to lift the part of magnetic material and raise and open the valve, the latter being restored to a closed position by gravity when the magnet is de-energized; and means for energizing the magnet.

In testimony whereof, we have signed our names to this specification.

EDWARD A. TABER.
ANDREW G. SPINNEY.
